UNITED STATES PATENT OFFICE.

HENRY J. MENARD, OF CHICAGO, ILLINOIS, ASSIGNOR TO H. R. MANUFACTURING COMPANY, OF CHICAGO, ILLINOIS, A CORPORATION OF ILLINOIS.

LOCK FOR CONTROLLING LEVERS.

Application filed March 6, 1917. Serial No. 152,596.

To all whom it may concern:

Be it known that I, HENRY J. MENARD, a citizen of the United States, residing at Chicago, in the county of Cook and State of Illinois, have invented certain new and useful Improvements in Locks for Controlling Levers, of which the following is a specification.

This invention relates to locks for controlling levers, and particularly to a device whereby the construction and application of such locks is simplified. It is an object of the invention to make it possible to apply a lock such as described in the co-pending application of Saxton and Menard, Serial No. 152,927, filed March 6, 1917, to any lever without material modification of the lever or accurate drilling and boring, etc., being done upon it.

20 In the drawings:—

Fig. 1 is a cross sectional view of the invention shown as applied to the controlling lever for an automobile.

Fig. 2 is a similar view upon another line. 25 Fig. 3 is a cross sectional view on line 3—3 of Fig. 2, the lock casing 5 being omitted.

In the drawings, 1 represents generally the casing for the ball 2 of the controlling lever 3, the casing 1 being provided in this case 30 with a conical recess 4 at its upper end, surrounding the lever 3. 5 represents a lock casing adapted to be pressed downwardly by the foot, and when so pressed to automatically engage the lever so that the downwardly projecting annular portion 6 of the casing 5 becomes firmly and rigidly locked in the casing 1, preventing movement of the lever. A tumbler lock 7 operates a plunger or bolt 8 to perform a locking function in the 40 fashion clearly indicated in the co-pending application referred to.

In a device constructed in accordance with the co-pending application, however, it is necessary to accurately fit the slideable element to the controlling lever, and to bore accurately positioned holes in the controlling lever to take the locking bolt 8. In a device constructed in accordance with my invention, I make this unnecessary by the employment 45 of a uniform sleeve 9 in which is drilled a hole for the locking bolt 8, the casing being locked directly to the sleeve 9. The sleeve 9 is keyed or otherwise rigidly secured to the lever. Within the sleeve 9 I place, if necessary, a sleeve 10, which may be supplied

in the right size to fit upon any controlling lever, and which is firmly secured upon the controlling lever or keyed or otherwise firmly secured thereto. The sleeve 9 carries bolt 11, to form an abutment for the spring, 60 which operates the casing 5.

It is, of course, understood that the sleeve 10 may be dispensed with if desired, the sleeve 9 being fitted at its upper end, (by being drilled out if necessary,) to the lever and 65 being sufficiently secure without the sleeve 10. But where the lever is of uniform diameter as shown, the sleeve 10 may be employed as a supplement to the standard outfit, compressing the sleeve 9 to insure additional 70 stability; the bolt or key which locks the sleeve 9 also passing through the sleeve 10, if thought desirable.

It is also possible to make the locks uniform and supply them with uniform sleeves 75 9 large enough to fit any lever, and to supply the extra sleeve 10, which may be carried in different sizes, or may be very easily made and which simply serves as a bushing, and fasten it upon the controlling lever 3. My 80 invention renders it unnecessary to make different sized locks, or to drill carefully aligned and positioned holes in the lever.

Having now described my invention, I claim:—

1. In a lock for controlling levers, a member adapted to be rigidly fixed to the controlling lever, a locking member slidably and non-rotatably mounted on said first member and carrying therein a locking element, and means encased within said slideable member for automatically raising said slideable member out of locking position when the locking element is released.

2. In a lock for controlling levers, a member slideable upon the controlling lever and having a locking element, said member being adapted to lock the lever in one of its positions thereon, means rigidly mounted upon the controlling lever with which the locking element in said slideable member is adapted to engage, and means interposed between said last mentioned member and said controlling lever, whereby the lock may be readily adapted to control levers of various 105 sizes.

3. In a lock for controlling levers, an adapter member adapted to be rigidly mounted upon the controlling lever, a locking member slidably and non-rotatably 110

mounted on said adapter member and having a lock bolt, said adapter member having means to receive the locking bolt in one position of the locking member, the adapter member also constituting means for adapting a given size locking member to levers of various sizes.

In witness whereof, I hereunto subscribe my name to this specification in the presence of two witnesses.

HENRY J. MENARD.
